UNITED STATES PATENT OFFICE.

FREDERICK W. C. NEUNER, OF CONNERSVILLE, INDIANA, ASSIGNOR, BY MESNE ASSIGNMENTS, TO INDIANA LAMP CORPORATION, OF CONNERSVILLE, INDIANA, A CORPORATION OF DELAWARE.

ELECTRIC CONNECTING SOCKET.

Application filed February 26, 1923. Serial No. 621,247.

This invention relates to a double contact connecting socket adapted to receive an incandescent lamp bulb in one end and an electrical contact plug in the other end.

5 The object of the invention is to provide a cushion insert connection within the socket of the most simple construction for yieldingly maintaining the lamp bulb and plug locked in position while at the same time 10 making an electrical connection therebetween.

The main feature of the invention lies in the provision of a cylindrical socket having an electric cushion insert connection 15 removably placed therein formed of a pair of insulating disks connected by means of a spring which serves not only as an electrical conductor, but as a resilient cushion spring, the ends of said spring being secured to the disks by means of contact buttons or other similar means. This does away with a more elaborate and expensive construction commonly employed for obtaining the same results.

25 The full nature of the invention will be understood from the accompanying drawings and the following description and claims.

In the drawings Fig. 1 illustrates a 30 socket having a portion thereof shown in cross section. Fig. 2 is an enlarged central vertical section taken through the cushion insert connection. Fig. 3 is an end elevation of the insert connection. Fig. 4 is the same as Fig. 2 showing a modified form. Fig. 5 is an end elevation of Fig. 4. Fig. 6 is the same as Fig. 2 showing a second modified form. Fig. 7 is an end elevation of Fig. 6.

40 In the drawings there is shown the usual type of cylindrical electric lamp socket 10 having bayonet slots 11 therein for supporting the body 12 of the lamp 13 in one end and the plug 14 in the other end. The body 45 12 and the socket 14 are provided with the usual pins 15 for engaging in the bayonet slots 11, whereby they will be locked therein by the resilient spring pressure exerted against their inner ends.

50 The cushion insert connection is adapted not only to make electrical contact between the socket 14 and the lamp 13, but exert an outward pressure thereon for maintaining the pins 15 locked in the bayonet slots

11. Said connection comprises a pair of 55 insulating washers or disks 16 and 17 of such diameter as to snugly fit within the cylinder 10. The disks are provided with central openings in which are secured the contact buttons 18 and 19 for engaging with 60 and making electrical contact with the contact point 20 of the lamp 13 and the contact point of the plug 14. Between the disks 16 and 17 and connecting them with each other, there is provided a spiral compression 65 spring 21 having one end in gripping contact about the grooved neck portion 22 of the contact 18 and the other end gripped about the grooved neck portion 23 of the contact 19.

70 By means of the above construction it will be observed that the cushion insert connection may be formed separately from the socket and simply spaced therein so as to lie between the lamp and the plug 14. 75 Upon the lamp and plug being secured in the ends of the socket they will engage the contact buttons 18 and 19 and force them toward each other against the tension of the spring 21. This will have the reverse effect 80 of forcing the lamp and plug away from each other so as to cause the pins 15 to lock in the bayonet slots 11. In addition to the spring 21 acting as a cushion and locking 85 spring, it will conduct a current from the plug 14 through the button 19 to the button 18 and lamp 13, without the necessity of embodying an additional contact means therebetween.

90 In the form shown in Fig. 4 the spring 121 has its ends inserted through diagonal holes 122 formed in the disks 116 and 117, after which the ends 118 and 119 of said spring are coiled so as to lock the disks 95 and spring together, and at the same time serve as contact buttons in place of the buttons 18 and 19.

100 In the modified form shown in Fig. 6 the disks 216 and 217 are provided with central openings through which the metal tubular members 218 and 219 are inserted after having the ends of the spring 221 locked about their inner grooved ends 222. The ends of the members 218 and 219 may then be hammered so as to spread and lock the same 105 within the disks, thereby forming contact buttons, as shown therein.

The invention claimed is:

1. A lamp socket comprising a tubular shell open at both ends adapted to receive a pair of electrical fixtures therein, a pair of insulating disks spaced apart and slidably mounted within said shell, and a contact spring positioned between said disks having the ends thereof so positioned as to make electrical contact with said fixtures and yieldingly maintain said disks in spaced relation.

2. A lamp socket comprising a tubular shell open at both ends adapted to receive a pair of electrical fixtures therein, a pair of insulating disks spaced apart and slidably mounted within said shell, a contact spring positioned between said disks for yieldingly spacing them apart and against said fixtures, and a contact button secured within each of said disks and positioned to make electrical contact with said fixtures and through said spring.

3. A lamp socket comprising a tubular shell open at both ends adapted to receive a pair of electrical fixtures therein, a pair of insulating disks spaced apart and slidably mounted within said shell, a contact button secured on each of said disks in position to engage and make contact with said fixtures, and a spring positioned between said disks and electrically connected with said buttons for conducting an electric current between said fixtures and yieldingly forcing said disks apart and said buttons into contact therewith.

35. 4. A lamp socket comprising a tubular shell open at both ends adapted to receive

a pair of electrical fixtures therein, a pair of insulating disks spaced apart and slidably mounted within said shell, a contact button extending through each of said disks and having a grooved shoulder on the inner side thereof, said contact buttons being so positioned as to make electrical contact with their adjacent fixtures, and a spring positioned between said disks having its ends secured about the grooved shoulders of said buttons for securing said disks together and yieldingly forcing them apart.

5. In a lamp socket, a shell open at both ends and adapted to receive electric fixtures in said ends, a pair of discs formed of insulating material freely movable within said shell, contact members carried by said discs, and a spring formed of conducting material interposed between said discs and secured at its ends to the latter and in engagement with said contacts.

6. In a lamp socket, a shell open at both ends and adapted to receive electric fixtures in said ends, a pair of discs movable rotatably as well as longitudinal within said shell, contact members on the exterior faces of said discs, a coil spring of conducting material interposed between said discs and electrically connected with said contacts, and said coil spring disposed axially of said discs and of appreciably less diameter than the same.

In witness whereof, I have hereunto affixed my signature.

FREDERICK W. C. NEUNER.
